UNITED STATES PATENT OFFICE.

EDWIN R. MERRILL, OF COLUMBUS, OHIO, ASSIGNOR TO THE JEFFREY MANUFACTURING COMPANY, OF COLUMBUS, OHIO, A CORPORATION OF OHIO.

MINING MACHINE AND TRUCK.

1,142,348.

Specification of Letters Patent.

Patented June 8, 1915.

Application filed September 12, 1910, Serial No. 581,489. Renewed September 18, 1913. Serial No. 790,564.

To all whom it may concern:

Be it known that I, EDWIN R. MERRILL, a citizen of the United States, residing at Columbus, in the county of Franklin and State of Ohio, have invented certain new and useful Improvements in Mining Machines and Trucks, of which the following is a specification, reference being had therein to the accompanying drawing.

10 The principal object of the invention is to provide in a mining machine and truck an improved arrangement of controlling and power-transmitting elements preferably located on the truck, and adapted for driving or retarding the truck wheels and the cable reel with which the truck is provided.

Other objects will be apparent from the following specification.

In order to make the invention clearly understood a practical embodiment of the same is shown in the accompanying drawings, that form of the invention being chosen for illustration which is deemed the most convenient and efficient.

25 In the said drawings Figure 1 is a plan view of a mining machine and truck embodying the invention, some of the forward portions of the machine and truck being broken away or omitted as not necessary to 30 an understanding of the invention. Fig. 2 is a side view of the same. Fig. 3 is a rear end view of the mining machine. Fig. 4 is a vertical cross section of the mining machine on line 4—4 of Fig. 2, certain of 35 the parts being shown in rear elevation. Fig. 5 is a vertical sectional view of the multiple disk friction clutch, and neighboring parts, on line 5—5, Fig. 2. Fig. 6 is a plan view of the same, partly in section.

40 In the drawings I have shown a mining machine of the breast type, but it will be understood that so far as the essential features of my invention are concerned the exact form of mining machine is immaterial.

45 The machine shown has a frame comprising two parallel side channel bars 2 cut to the desired shape. The bars 2 are connected with each other at the rear of the machine by a cross-frame 5 fitting in the channels, 50 at the front end by a cross-bar 6, and at intermediate points by one or more cross-plates 7 arranged near the bottom of the frame out of the way of the carriage.

55 10 is a carriage comprising a front cross-bar 11 and rearward extending side bars 12,

12. The carriage is provided with rollers 13 which run on the tops of the main side bars 2.

14 is an electric motor which is mounted on the carriage and the frame of which 60 serves to connect the side bars 12 at their rear ends. The motor is arranged with its armature shaft horizontal and extending longitudinally of the machine. The carriage is guided for movement longitudinally of the frame by means of suitable projections formed on the cross-bar 11 and on the motor frame, and suitable lugs are also provided for preventing upward movement of the carriage away from the frame. 70

Connected to the carriage for movement therewith is a cutter frame 17 having a longitudinal guide bar 18 which slidably engages with suitable guides formed on the cross-member 6 of the main frame. The 75 cutter frame is adapted to support and guide a cutter chain of the usual type which, for the sake of simplicity, has been omitted from the drawings. The cutter chain is driven by means of the sprocket wheel 25 80 which will be again referred to.

Fixed on the front end of the armature shaft of the motor 14 is a bevel pinion 20 which meshes with a bevel gear 21 on a vertical shaft 23. The shaft 23 carries the 85 sprocket wheel 25 above referred to and this sprocket wheel can therefore be driven by the motor through the gearing which has been described. Preferably a clutch is provided for connecting or disconnecting the 90 gear wheel 21 with the shaft 23. This clutch is indicated at 27 in Figs. 3 and 4. It can be operated by means of the hand-lever 33.

38 is a transverse feed shaft mounted on 95 the carriage. It carries a worm-wheel 37 which meshes with a worm 36 on the vertical shaft 23. Slidably splined on the shaft 38 are driving clutch members 40 and 41, and for shifting these members there is 100 provided a yoke 42 operable by a hand-lever 43.

45 and 46 are driven clutch members on the shaft 38 and are adapted respectively to mesh with the members 40 and 41. The 105 clutch members 45 and 46 are connected respectively with gear wheels 47 and 52. The gear wheel 47 meshes directly with a gear wheel 48 on the transverse shaft 49. The gear wheel 52 meshes with an idler pinion 110

53 which in turn meshes with a gear wheel 54 on the shaft 49. At the ends of the shaft 49 are pinions 51, 51, mounted to mesh respectively with racks 51^a, 51^a, secured to 5 the main frame members 2. When the hand-lever 43 is moved in one direction power will be transmitted through the gears 47 and 48 to rotate the pinions 51, 51, in the direction to force the carriage and cutter frame forward with respect to the machine frame. When the hand-lever 43 is thrown in the other direction, power will be transmitted through the gears 52, 53 and 54 to cause the carriage and cutter 10 frame to be moved in the opposite direction. The yoke 42 can be moved automatically by means of the link 59 and the bell-crank 61. One arm of this bell-crank is adapted to engage the stops 62 and 63 on the main 15 frame when the carriage reaches its limit of movement in one direction or the other.

66 indicates the frame of the so-called self-propelling truck, which is employed for the transportation of the mining machine, 20 which truck is propelled by power derived, through suitable connections, from the mining machine motor.

67 is a transverse shaft mounted in bearings 68 on the truck frame 66, and 69 is a 25 sprocket fixed on the shaft 67 and connected by a chain 69^a with the ground or supporting wheels 69^b of the truck to propel the latter.

70 is a worm wheel loosely mounted on 30 the shaft 67 and adapted to be clutched more or less tightly to the shaft by a multiple disk friction clutch 71 also mounted on the said shaft and contained within an enlargement or box 72 of the bearings 68.

40 This friction clutch 71 is tightened or loosened by a hand wheel 73 on the shaft 67.

74 is a worm on a longitudinal shaft 75 and above and meshing with the worm wheel 70. It is contained within the box 72 45 and the shaft 75 is mounted in bearings 76 on the latter.

77 is a pin clutch, the two members of 50 which are fixed respectively on the front end of the worm shaft 75 and on the rear end of the armature shaft 19, these two clutch members being brought into mutual engagement in a known manner as and when the mining machine is loaded onto the truck.

By the arrangement described the controller or starting box of the mining machine motor can be thrown to the full "on" position and the speed of the truck varied by the hand wheel 73 and the friction clutch 71.

Mounted on the rear end of the 60 truck is a cable reel 78 adapted to wind up the cable, which carries the electric current to the motor, automatically as the truck and mining machine thereon come out of the room. On the hub of the reel 78 is a sheave 65 wheel 79 connected with a sheave 80, which

is loose on the clutch shaft 67, by a hemp rope 81. 82 is a clutch for connecting the sheave 80 with its shaft. The shape of the grooves in the sheaves is such that should the tension on the cable become too great 70 the rope 81 will slip on the sheave 80. There is thus provided a slipping, yielding or frictional take-up for the cable.

The friction clutch 71 comprises a set of annular plates 83 which are notched on their peripheries, the said notches engaging ribs 84 attached to or cast with the worm wheel 70 to cause the plates 83 and worm wheel to rotate together; and a set of annular plates 85 alternating with the plates 83 and internally notched to engage ribs 86 on the shaft 67. The two sets of plates are longitudinally loose except when more or less clamped together by the hand wheel 73. The clutch plates are confined between the body of the worm wheel and a movable collar 87, and the said confining parts are held between two sets of ball bearings 88 and 89. The ball bearings 89 are arranged between the worm wheel and a part of the frame 66, and the ball bearings 88 are between the collar 87 and the hand wheel 73. When the latter is forced against the ball bearing elements at 88 the plates 83 and 85 are caused to engage frictionally and the shaft 75 caused to 95 revolve with the shaft 75, with more or less slippage according to the pressure of the hand wheel 73. The hand wheel is fixed on a screw threaded sleeve 90 mounted on the shaft 67, and the sleeve 90 is screwed within a sleeve 91 fixed in a part of the frame 66. Consequently the turning of the hand wheel imparts endwise movement to itself to compress or release the friction elements of the clutch 71.

It will be observed that the upper surfaces of the parallel longitudinally arranged side bars or supporting rails of the truck frame 66 are smooth and are unobstructed when the mining machine is not in place. This construction and arrangement make it possible for the mining machine to be readily slid along the rails into or out of the position in which it is shown in Figs. 1 and 2 of the drawings. The power receiving element of the truck (in this case the clutch member at the forward end of the shaft 19) is exposed on the side toward the space reserved for the mining machine, thus making it possible for the mining machine to engage the said element when the machine is moved into position.

It will be clear that the worm and worm wheel constitute a non-overhauling power transmitting mechanism, that is, power can be transmitted in one direction from the worm to rotate the worm wheel, but power cannot be transmitted in the other direction from the worm wheel to rotate the worm. The provision of this non-overhauling 120

adapts the friction clutch 71 to automatically act as a brake for the track wheels. When power is being applied at the clutch 77 it is transmitted through the worm and 5 the worm wheel and the friction clutch to the sprocket wheel 69 and to the wheels. But when no power is being applied at the clutch 77 the worm 74 does not rotate and serves to lock the worm wheel and one element of the 10 clutch 71 against rotation. This locked element of the clutch engages the other element which is connected with the wheels and retards its rotation together with that of the wheels. It will be seen that in this way I 15 have provided means for transmitting power from the clutch 77 to the truck wheels when the clutch is driven and for automatically applying a frictional resistance to the rotation of the wheels when the clutch is not 20 driven.

I am aware that it has heretofore been proposed to provide for a mining machine truck of the type herein shown a cable reel connected to be driven simultaneously with 25 the truck wheels. I do not, therefore, broadly claim such a cable reel and its connections as a part of this invention. However, I believe myself to have been the first to provide in an apparatus of this character, 30 a manually controllable friction clutch between the mining machine and the truck wheels and reel. This clutch not only serves as a means for manually controlling the transmission of power from the motor to 35 the wheels and reel, but also, in combination with the worm and worm wheel, serves as a brake to resist rotation of the wheels and reel when the motor is idle.

What I claim is:—

40 1. In a mining machine and truck therefor, the combination of a wheeled truck, a mining machine mounted on the truck but adapted to be readily removed therefrom, and a train of power transmitting elements 45 between the motor of the mining machine and the truck wheels comprising two elements adapted to be connected or disconnected by the bodily movement of the machine as a whole on the truck and a manually operable clutch supplemental to the 50 said two elements.

2. In a mining machine and truck therefor, the combination of a wheeled truck, a mining machine mounted on the truck but 55 adapted to be readily removed therefrom, and a power transmitting mechanism between the motor of the mining machine and the truck wheels comprising two independently movable frictionally engaging elements and two other elements adapted to be connected or disconnected by the bodily movement of the machine as a whole on the truck.

3. In a mining machine and truck therefor, the combination of a wheeled truck, a

mining machine mounted on the truck but adapted to be readily removed therefrom, and means for transmitting power from the motor of the mining machine to the truck wheels when the said motor is energized and 70 for automatically applying a frictional resistance to the rotation of the wheels when the motor is not energized.

4. In a mining machine and truck therefor, the combination of a wheeled truck, a 75 mining machine mounted on the truck but adapted to be readily removed therefrom, and a separable power transmitting mechanism between the motor of the mining machine and the wheels of the truck comprising 80 a worm connected with the motor, a worm wheel meshing with the worm and a friction clutch between the worm wheel and the truck wheels, the worm serving when the motor is idle to lock one of the elements 85 of the friction clutch against rotation when the said element is not driven by the motor.

5. In a mining machine and truck therefor, the combination of a wheeled truck, a mining machine mounted on the truck but 90 adapted to be readily removed therefrom, a separable power transmitting mechanism between the motor of the mining machine and the wheels of the truck comprising a worm connected with the motor, a worm wheel 95 meshing with the worm and a friction clutch between the worm wheel and the truck wheels, the worm serving when the motor is idle to lock one of the elements of the friction clutch against rotation when the said 100 element is not driven by the motor, and manually operable means for adjusting the pressure between the elements of the friction clutch.

6. In a mining machine and truck therefor, the combination of a wheeled truck, an electric mining machine mounted on the truck but adapted to be readily removed therefrom, a rotatable cable reel on the truck, an electric conductor cable on the 105 reel, means for transmitting current from the cable to the motor of the mining machine, and a separable power transmitting mechanism interposed between the said motor on the one hand and the truck wheels 110 and reel on the other hand comprising a manually operable clutch.

7. In a mining machine and truck therefor, the combination of a wheeled truck, an electric mining machine mounted on the 115 truck but adapted to be readily removed therefrom, a rotatable cable reel on the truck, an electric conductor cable on the reel, means for transmitting current from the cable to the motor of the mining machine, and a separable mechanism interposed between the 120 said motor on the one hand and the truck wheels and reel on the other hand for transmitting power from the motor to the wheels 125 and reel or for applying a manually regula- 130

ble resistance to the rotation of the wheels and reel.

8. In a mining machine and truck therefor, the combination of a wheeled truck, an electric mining machine mounted on the truck but adapted to be readily removed therefrom, a rotatable cable reel on the truck, an electric conductor cable on the reel, means for transmitting current from the cable to the motor of the mining machine, and a separable mechanism for transmitting power from the said motor to the truck wheels and reel when the motor is energized and for automatically applying a frictional resistance to the rotation of the wheels and reel when the motor is not energized.

9. In a mining machine and truck, the combination of a wheeled truck, cutter-carrying-mechanism on the truck, a motor, power transmitting mechanism between the motor and the cutter - carrying mechanism comprising a manually operable clutch, and means for transmitting power from the motor to the truck wheels when the motor is energized and for automatically applying a frictional resistance to the rotation of the wheels when the motor is not energized.

10. In a mining machine and truck, the combination of a wheeled truck, cutter-carrying mechanism on the truck, an electric motor, power transmitting mechanism between the motor and the cutter-carrying mechanism comprising a manually controllable clutch, a rotatable cable reel on the truck, an electric conductor cable on the reel, means for transmitting current from the cable to the motor, and means for transmitting power from the motor to the truck wheels and reel when the motor is energized and for automatically applying a frictional resistance to the rotation of the wheels and reel when the motor is not energized.

11. In a mining machine truck, the combination of a low frame having longitudinally arranged mining machine supports with their upper surfaces unobstructed, supporting wheels for the frame, an exposed power receiving element on the frame adjacent the said mining machine supports, and a train of power transmitting elements between the said power receiving element and the truck wheels comprising a manually operable clutch, the said elements being positioned to leave unobstructed the space above the mining machine supports.

12. In a mining machine truck, the combination of a low frame having longitudinally arranged mining machine supports with their upper surfaces unobstructed, supporting wheels for the frame, an exposed power receiving element on the frame adjacent the said mining machine supports, and a power transmitting mechanism between the said power receiving element and the truck wheels comprising two independ-

ently movable frictionally engaging elements, the said mechanism being positioned to leave unobstructed the space above the mining machine supports.

13. In a mining machine truck, the combination of a low frame having longitudinally arranged mining machine supports with their upper surfaces unobstructed, supporting wheels for the frame, an exposed power receiving element on the frame adjacent the said mining machine supports, and means for transmitting power from the said power receiving element to the truck wheels when the said element is driven and for automatically applying a frictional resistance to the rotation of the wheels when the said element is not driven, the said power transmitting means being positioned to leave unobstructed the space above the mining machine supports.

14. In a mining machine truck, the combination of a low frame having longitudinally arranged mining machine supports with their upper surfaces unobstructed, supporting wheels for the frame, an exposed power receiving element on the frame adjacent the said mining machine supports, a worm connected with the said power receiving element to be driven thereby, a worm wheel meshing with the worm, and power connection between the worm wheel and the truck wheels comprising a friction clutch, the worm serving to lock one of the elements of the friction clutch against rotation when the said power receiving element is not driven.

15. In a mining machine truck, the combination of a low frame having longitudinally arranged mining machine supports with their upper surfaces unobstructed, supporting wheels for the frame, an exposed power receiving element on the frame adjacent the said mining machine supports, a worm connected with the said power receiving element to be driven thereby, a worm wheel meshing with the worm, power connections between the worm wheel and the truck wheels comprising a friction clutch, the worm serving to lock one of the elements of the friction clutch against rotation when the said power receiving element is not driven, and manually operable means for adjusting the pressure between the elements of the friction clutch.

16. In a mining machine truck, the combination of a low frame having longitudinally arranged mining machine supports with their frame surfaces unobstructed, supporting wheels for the frame, an exposed power receiving element on the frame adjacent the said mining machine supports, a rotatable cable reel on the truck, and a train of power transmitting elements between the said power receiving element on the one hand and the truck wheels and reel on the

other hand comprising a manually operable clutch.

17. In a mining machine truck, the combination of a low frame having longitudinally arranged mining machine supports with their frame surfaces unobstructed, supporting wheels for the frame, an exposed power receiving element on the frame adjacent the said mining machine supports, a rotatable cable reel on the truck, and mechanism between the said power receiving element on the one hand and the truck wheels and reel on the other hand for transmitting power from the said element to the wheels and reel or for applying a manually regulable resistance to the rotation of the wheels and reel.

18. In a mining machine truck, the combination of a low frame having longitudi-

nally arranged mining machine supports with their frame surfaces unobstructed, supporting wheels for the frame, an exposed power receiving element on the frame adjacent the said mining machine supports, a rotatable cable reel on the truck, and means for transmitting power from the said power receiving element to the truck wheels and reel when the said element is driven and for automatically applying a frictional resistance to the rotation of the wheels and reel when the said element is not driven.

In testimony whereof I affix my signature, in presence of two witnesses.

EDWIN R. MERRILL.
